CAN TEAR STRIP GUIDE AND MEASURING CUP

Roger M. Snook, San Francisco, Calif.

Application April 4, 1950, Serial No. 153,858

9 Claims. (Cl. 220—52)

1

This invention relates to a can opener guide and, more particularly, to a device which is operable to act as a guide for the metal band of key opening cans and the like.

In cans of the type having a separable and detachable metal band disposed about the can body adjacent the lower edge of the lid, slotted keys are provided for the purpose of winding the band to open the can. In opening cans of this character with slotted keys, difficulty is frequently encountered owing to the fact that the reel or coil of the winding band often slips to one side or the other, which will occur unless care is exercised during this operation. Frequently this occurrence necessitates rewinding of the band, or else cutting it off to provide a short projecting end for taking a new hold on the band with the key.

These difficulties are extremely bothersome to the average householder. Also cuts frequently result from mishaps of this character, and even though the winding operation may be concluded successfully, the sharp, exposed edges of the winding band are always a hazard.

It is an object of the present invention to provide an improved form of guide for guiding a slotted key or other tool in opening cans of the character described.

It is a further object of the invention to provide a can opener guide of the character and for the purpose described which will prevent the coil of winding band from slipping or from turning from its intended path.

A still further object of the invention is to provide a can opener guide of the character and for the purpose described which is operable to guide a slotted key and the coil of the winding band during the winding operation, which is simple in its construction and operation.

It is still another object of the invention to provide a can opener guide of the character and for the purpose described which can be re-used indefinitely.

Yet another object of the invention is to provide a can opener guide of the character and for the purpose described which has associated uses other than that of a guide.

These and other objects of the invention will be apparent from the ensuing description and appended claims.

Certain forms which the invention may assume are exemplified in the following description and illustrated by way of example in the accompanying drawings in which:

Figure 1 is a perspective view of one form of can opener guide constructed in accordance with

2

my invention, showing the same in the act of guiding a key and the coil of the winding band.

Figure 2 is a bottom view of the can opener guide of Figure 1.

Figure 3 is a longitudinal section taken along the line 3—3 of Figure 2.

Figure 4 is a bottom view of another form of can opener guide constructed in accordance with the present invention.

Figure 5 is a view partly in side elevation and partly in longitudinal section taken along the line 5—5 of Figure 4.

Referring now to the drawings and more particularly to Figures 1, 2 and 3, there is shown one

form of can opener guide which is generally designated as 10. In Figure 1, the can opener guide 10 is shown in conjunction with a can 11 having a body 12, a lid 13 and a winding band 14. As

is usual with cans of this character, a slotted key

15 is provided which is intended to fit over a loose end or tongue of the winding band to start the winding operation to open the can and separate the lid from the body.

As is well known, as the key 15 is turned in a clockwise direction, as viewed in Figure 1, the winding band 14 is formed into a coil 16 and as it is wound or detached from the can it leaves a peripheral groove 17 which separates the body 12 from the lid 13. This allows removal of the lid when the band 14 has been completely detached.

As illustrated, the can opener guide 10 comprises a guide portion proper, which is indicated generally as 18 and will be referred to hereinafter as the "guide," and this guide also serves as a handle for a measuring cup 19, there being provided, if desired, a reinforcing rib 20. The measuring cup 19 may be of any convenient size; for example, to measure out a teaspoon or tablespoon. It is apparent that the measuring cup 19 may be of any suitable shape, or may be replaced with some other suitable implement or design, or may be dispensed with entirely.

The can opener guide 10 may be molded in one integral piece from plastic, or it may be made from metal, or from any other suitable material of construction and by any suitable method. It will be apparent that the device can be manufactured at very little expense and in any desired quantity.

The guide 18 is a generally flat, relatively narrow, elongated member. It is bent at its outer end into a U-shape to form a tail or end portion 25 which underlies the upper body portion and is spaced therefrom to provide a groove or keyhole 26. As will be seen the end portion 25

55

is constricted, or bent inwardly at its outer end, as at 25a, to narrow somewhat the space between the end portion and the main body of the guide.

The guide 18 is also formed with a longitudinal slot 27 which is closed at its inner end and which extends to the end of the tail 25 so that the latter is, in effect, a bifurcated member. A reinforcing bridge or rib 29 is provided, as illustrated, which is recessed at 30 and is formed with a tip 31 for a purpose described hereinafter. The under surface of the bifurcated tail 25 and the rib 29 is curved at 32 so as to conform, more or less, to the surface of a can body 12.

In use, the can opener guide 10 is employed as follows: The loose tongue (not shown) of the can winding band 14 is pried upward, as by means of the tip 31. A slotted key such as shown at 15, is then fitted over the tongue in the usual manner and is given a turn or two to clamp it to the winding band and to place a flat side of the key adjacent the can. Then the key is seated in the guide 18 in the manner shown in Figure 1, by slipping the bifurcated tail 25 underneath the key. Also, the guide 18 is adjusted so as to register its slot 27 with the coil 16. The constriction at 25a although amply wide enough to easily admit the key 15 to the key hole 26, tends to keep the key in operating position. Hence, when the key is seated in the keyhole 26 it will have no tendency to unseat or get out of position unless such result is desired intentionally.

After these adjustments have been made, the key is then turned to wind and detach the band 14 from the can body. During this operation, the guide 18 travels forward in relation to and at the same speed as the coil is being wound by the key, effectively guiding the key 15 and the coil 16. Thus, lateral support is provided for the coil to prevent slippage or springing of the coil in an axial direction. Also, the guide is of sufficient bulk that it will resist turning of the key from its intended path of movement about the unwinding band 14, and its curved under surface 32 helps to guide it and the key and coil. Moreover, the guide also acts to shield the sharp edges of the unwinding band and coil, thereby preventing hazards due thereto.

A further advantage of the device of this invention resides in the fact that it can be very easily detached and re-used. This can be accomplished by unwinding the coil 16, or merely by moving the cup end of the device toward the key with sufficient force to pass the key (with the coil) through the restriction of the ends of the bifurcated tail 25, so as to release the key from the keyhole 26.

Referring now to Figures 4 and 5, a modified form of can opener guide 10a is there illustrated in which the guide portion 18a is similarly slotted at 27 and is formed at its outer end into a U-shaped, bifurcated tail or end portion 25. However, an extension 35 is also provided which extends outwardly from the bifurcated tail 25 and which is slotted, as at 36. The slot 36 joins and constitutes a continuation of the slot 27. As shown, reinforcement ribs 38 may also be provided.

This form of device is advantageous where, because of the diameter of the can, or the thickness of the winding band, a coil of relatively large diameter is produced before the opening process has been completed. Thus, the slot 36, being an extension of the slot 27, accommodates a coil 16 of substantial diameter.

It will thus be apparent that a can opener

guide has been provided which satisfies several objects. It is simple from the standpoint of manufacture and operation; it is re-usable indefinitely; it can be constructed from an inexpensive material and by inexpensive methods, such as molding from plastic; and it very effectively performs the function of guiding a key and the coil of removable sealing band.

I claim:

1. A device of the character described comprising a member having a closed longitudinal slot formed therein to guide the coil of winding band as the same is detached from a can body and coiled about a key said member also having a surface for contact with said can ahead of said slot, and clip means transverse to and adjacent said slot and in registry therewith to rotatably receive and removably retain a key during detachment of said band and to permit immediate disposal of said key and wound band.

2. A device of the character described comprising a slotted member for guiding the coil of winding band as it is detached from a can body and coiled about a key said member also having a surface for contact with said can ahead of said slot, and a clip key retainer means in registry with the slot in said member and transverse thereto for rotatably receiving and removably retaining a key permitting immediate disposal of said key with the wound band.

3. A device of the character described comprising a body member having a closed longitudinal slot formed therein to guide the coil of winding band as the same is detached from a can body and coiled about a key said member also having a surface for contact with said can ahead of said slot, and a transverse slotted key retainer member disposed below and spaced from said body member and in registry with the slot formed therein permitting immediate removal and disposal of said key with the wound band.

4. A device of the character described comprising a body member having a closed longitudinal slot formed therein to guide the coil of winding band as the same is detached from a can body and coiled about a key said member also having a surface for contact with said can ahead of said slot, and bifurcated clip key retainer means transversely underlying said body member, spaced therefrom and in registry with the slot formed therein.

5. A device of the character described comprising a flat elongated member formed at one end into a U-shape to define a clip recess for receiving a can opener key, said member being also formed with a closed longitudinal slot transverse thereto to guide the coil of winding band as the same is detached from a can body and is coiled about a key said member also having a surface for contact with said can ahead of said slot, said slot extending along said member on both sides of said recess and being open at one end to allow insertion, temporary retention and removal of a can opener key with the detached wound band.

6. A can opener guide comprising an elongated, closed longitudinally slotted body portion said member also having a surface for contact with said can ahead of said slot and a relatively short bifurcated end portion underlying one end of said body portion in registry therewith and spaced a short distance therefrom sufficient to transversely receive and temporarily retain a can opener key and to immediately release the key with the wound band thereon.

7. A can opener guide comprising an elongated

body portion having a closed longitudinal slot formed therein to guide the coil of winding band as the same is detached from a can body and is coiled about a key said member also having a surface for contact with said can ahead of said slot, and a key retainer member fixed to and spaced from said body portion to define a U-shaped recess for removably receiving a can opener key, said key retainer member being bifurcated to form a continuation of the slot in said body portion, said continuation being open at its outer end but closed enough to retain the key in position while permitting frictional removal of the key with the wound band thereon.

8. A can opener guide comprising an elongated body portion having a longitudinal slot formed therein to receive a coil of winding band as the same is detached from a can body and is coiled about a key, and a key retainer member fixed to and spaced from said body portion to define a U-shaped recess for receiving a can opener key, said key retainer member being bifurcated to form a continuation of the slot in said body portion, said continuation being open at its outer end, said body portion being formed at one end with a prying member and having a measuring cup fixed to its other end.

9. A can opener guide comprising an elongated body portion having a closed longitudinal slot formed therein to guide the coil of winding band as the same is detached from a can body and is coiled about a key said member also having a surface for contact with said can ahead of said slot, and a clip key retainer member fixed to said body portion intermediate the ends of said slot and spaced therefrom to define a U-shaped recess for receiving a can opener key, said key retainer member being bifurcated to form an open-ended continuation or branch of said slot for rotatably holding said key and immediate release of said key and wound band thereon.
